ABSTRACT OF THE DISCLOSURE

Each of the branches of a demodulator bridge circuit comprises a pair of resistors connected in series between a corresponding pair of junctures. At least one capacitor is connected in one of the branches in series with the resistors thereof and between a juncture and one of the resistors. One of the electrodes of each of a plurality of diodes connected to a corresponding one of the branches at a common point in the connection between the two components of the branch. The diodes are connected with each pair thereof connected in series between common points of opposite branches of the bridge circuit connected in opposed polarity relationship. The polarities of the diodes of one pair, connected to the common points, are opposite the polarities of the diodes of the other pair connected to the common points.

The present invention relates to a circuit arrangement by means of which it is possible to adjust the operating point for the nonlinear impedances being crossconnected in a cross modulator or demodulator and in consequence to gain better transmission parameters, e.g. a decreased nonlinear distortion, a variable angle of the opening of the diodes, a convenient adaptability to the monophone reception conditions in stereophony etc.

Known cross modulators are shown in FIGS. 1 and 2. They comprise four nonlinear impedances, e.g. diodes $D_1 \dots D_4$, all of them being interconnected by one electrode at a common point, the other electrode of each diode being connected always between two resistors, forming a branch of a bridge. The diodes $D_1 \dots D_4$ are poled in the way that the same pole of one pair of the said diodes is connected to one couple of the opposite points in the branches of the bridge and the contrary pole of the second pair of the said diodes is connected to the appropriate couple of the opposite points in the branches of the bridge.

The carrier wave is applied to the junctures a, c of the bridge formed by the impedances R_1 to R_8 . The modulating signal or modulating signals are applied to the junctures b, d . The four non-linear impedances D_1 to D_4 are interconnected at one point V which represents simultaneously also the output from the modulator. If the circuit operates as a synchronous balanced demodulator according to this description, the modulated signal or the both modulated signals are applied to the terminals b, d and the output is then at the point V . On the other hand the modulated signal can be applied to the point V and the output of demodulated signals is at the points b, d .

The drawback of both the above mentioned circuit arrangements is that the normal operating point (if the modulation is not applied to the carrier wave) of the diodes is determined by the zero voltage on their characteristics. The opening point adjusted in this way is not always the most convenient. By means of the circuit arrangement according to the invention it is possible to

2

attain either that both diodes get their negative bias resulting in an opening decrease of their angle or that the positive bias is applied to the diodes, the opening angle being increased. By shifting the operating point upon the characteristic it is possible to change the relative value of the individual frequency components on the modulator or demodulator output.

Due to a circuit arrangement in accordance with the invention new and very important properties were gained not available in the original circuit arrangement.

The circuit arrangement is characterized in that at least in one branch of the modulator bridge the non-linear impedance, e.g. diode, is connected to one pole of a DC source through impedances, whereby in one of the adjacent branches another point to which a diode is connected, is joined with the other pole of the DC source through the impedances. The impedances connecting the said two points with the DC source E_s may be also the impedances which form part of the branches of the modulator bridge.

The invention will be best understood from the following specification to be read in conjunction with the accompanying drawings in which:

FIGS. 1 and 2 illustrate the known circuit arrangements.

FIG. 3 shows the cross modulator with resistors in the respective branches.

FIG. 4 shows a special circuit arrangement of the modulator.

FIG. 5 is similar circuit arrangement to FIG. 4, but is a synchronous demodulator.

FIG. 6 shows a circuit arrangement with only one capacitor in series with the resistors.

FIG. 3 illustrates an example of the use of the invention for the cross modulator, the branches of which consist of the impedances R_1 and R_2 to R_7 and R_8 .

In this case a doublefold use of the circuit arrangement according to the invention is available. The points X_1 and X_2 within the two branches, in which the diodes D_1 and D_3 are interconnected, are connected to one pole of the DC source E_s through the impedance R_x , whereby the points Y_1 and Y_2 in the adjacent branches from which the diodes D_2 and D_4 are supplied are connected to the second pole of the DC source E_s through the impedance R_y .

FIG. 4 illustrates an arrangement in accordance with the invention when the impedances connecting the bridge points, from which the diodes are supplied, are joined with the DC source and are a part of the modulator bridge branches. Two capacitors C_1 and C_2 are connected in series with the impedances R_1 and R_5 forming the modulator bridge. The bridge is divided thereby into two branches with respect to the DC current. The opposite electrodes of both capacitors are connected through the impedances R_9 and R_{10} to one pole of the DC source, whereas the two remaining opposite electrodes are connected with the second pole of the DC source through the impedances R_{11} and R_{12} . FIG. 5 shows an example of such an arrangement for the synchronous demodulator, where the auxiliary carrier wave is applied to the bridge by means of a tuned circuit consisting of a capacitor C and an inductor L .

FIG. 6 illustrates an arrangement in accordance with the invention where only one capacitor C_3 is connected in series with the impedances R_1 and R_6 . With respect to the DC current the bridge is thus divided at one spot only. One electrode of the capacitor C_3 is connected through the impedance R_9 with one pole of the DC source E_{ss} and the second electrode through the impedance R_{10} to the second pole of the DC source. The common point of all four diodes is divided with respect to the DC current by one or more capacitors in two parts,

e.g. according to FIG. 6 by means of two capacitors K_1 and K_2 . With respect to the AC current, however, all four diodes are interconnected at one common point V .

In the circuit arrangement of FIG. 4, the problem of passing a specific small current through the diodes is solved in the simplest manner. Two DC circuits are provided in the demodulator, so that two DC currents flow. The first current, from the DC voltage source E_{ss} , flows through the resistors R_9 to the juncture a , through the resistor R_8 , the diode D_4 , the diode D_3 , the resistor R_5 and the resistor R_{11} to ground. The second current, from the DC voltage source E_{ss} , flows through the resistor R_{10} to the juncture c , through the resistor R_4 , the diode D_2 , the diode D_1 , the resistor R_1 and the resistor R_{12} to ground.

If $R_9=R_{10}$, $R_8=R_4$, $R_2+R_3=R_7+R_6$, $R_1=R_8$ and $R_{12}=R_{11}$, both currents flowing in FIG. 4 provide an identical potential at the common point of connection of the diodes. The pairs of diodes D_4 , D_3 and D_1 , D_2 thus do not need to be separated by capacitors.

If a resonant circuit is connected between a pair of junctures of the bridge, as shown in FIG. 5, the resistors $R_9=R_{10}$ of FIG. 4 may be omitted. In FIG. 5 the DC voltage source E_{ss} is connected to the center of the inductor L of the resonant circuit comprising said inductor and a capacitor C connected in parallel between the junctures a and c .

In FIG. 6, only one capacitor C_3 is connected in a branch of the bridge. There is thus a single DC circuit. The current flows from the DC voltage source E_{ss} through the resistor R_9 to the juncture a , through the resistor R_8 , the corresponding pair of diodes, the resistor R_5 , the resistor R_4 , the other pair of diodes, the resistor R_1 and the resistor R_{10} to the DC voltage source E_{ss} . Since a small current flows through the diodes the operating point is shifted from zero and the diodes have a specific defined resistance. If there is no carrier wave, there is no modulation or demodulation distortion.

What I claim is:

1. A demodulator, comprising a plurality of diodes connected with one of the electrodes of each connected to a common point; a plurality of resistors; a capacitor means comprising at least one capacitor; a bridge circuit having a plurality of branches and a plurality of junctures, each of said junctures being at the point of intersection of adjacent branches, each of said branches comprising a pair of said resistors connected in series between a corresponding pair of junctures, at least said capacitor being connected in one of said branches in series with the resistors thereof and between a juncture and one of said resistors, the other electrode of each of said diodes being connected to a corresponding one of said branches at a common point in the connection between the two resistors of said branch, said diodes being connected in a manner whereby each pair thereof connected in series between common points of opposite branches of said bridge circuit is connected in opposed polarity relationship, the polarities of the diodes of one pair connected to said common points being opposite the polarities of the diodes of the other pair connected to said common points; impedance means and additional impedance means;

5 a source of DC voltage having one polarity terminal connected to one electrode of said capacitor via said impedance means and an opposite polarity terminal connected to the other electrode of said capacitor via said additional impedance means; means for supplying a modulated carrier wave to the common point of said diodes; means for providing a carrier wave at a pair of said junctures; and means for providing a demodulated wave at another pair of said junctures.

2. A demodulator as claimed in claim 1, wherein said capacitor means comprises a pair of capacitors, one of which is connected in one of said branches in series with the resistors thereof and between a juncture and one of the resistors of said one of said branches and the other of which is connected in another of said branches in series with the resistors thereof and between an opposite juncture and one of the resistors of said other of said branches.

3. A demodulator as claimed in claim 1, wherein each of said impedance and additional impedance means comprises a resistor, and further comprising a pair of capacitors each connected on a corresponding side of the common point of connection of said diodes in a manner whereby said pair of capacitors are interposed between the diodes of each of said pair of diodes.

4. A demodulator as claimed in claim 2, wherein the junctures to which the capacitors are connected are those at which a carrier wave is provided and each of said impedance means and additional impedance means comprises resistance means having resistors and each terminal of said DC voltage source is connected to each electrode of each of said capacitors via a different resistor of said resistance means.

5. A demodulator as claimed in claim 2, wherein the junctures to which the capacitors are connected are those at which a carrier wave is provided, said impedance means comprises resistance means having resistors, said additional impedance means comprises a resonant circuit connected between the junctures at which said carrier wave is provided and one terminal of said DC voltage source is connected to one electrode of each of said capacitors via a different resistor of said resistance means and the other terminal of said DC voltage source is connected to the other electrode of each of said capacitors via part of said resonant circuit.

6. A demodulator as claimed in claim 5 wherein said resonant circuit comprises an inductor and a capacitor connected in parallel between the junctures at which said carrier wave is provided and the other terminal of said DC voltage source is connected to the other electrode of each of the capacitors via part of the inductor of said resonant circuit.
